UNITED STATES PATENT OFFICE.

CHARLES OAKS SEAVEY, OF SOUTH FRAMINGHAM, MASSACHUSETTS.

DESIGN FOR A BOLT-OPERATOR AND NAIL-SET.

SPECIFICATION forming part of Design No. 31,001, dated June 13, 1899.

Application filed May 20, 1899. Serial No. 717,648. Term of patent 14 years.

To all whom it may concern:

Be it known that I, CHARLES OAKS SEAVEY, of South Framingham, in the county of Middlesex and State of Massachusetts, have invented and produced a new and original Design for a Bolt-Operator and Nail-Set, of which the following is a description.

The figure of the drawing is a perspective view showing my new design.

As shown in the drawing, the leading or material feature of the design consists of a square or four-sided tapering end portion *a*, the flattened form of the central part *b*, the rounded form of the edges *c* of the part *b*, and the rounded tapering form of the end portion *d*.

It is apparent that the design is applicable to many uses other than those stated in the title.

Having described my invention, I declare that what I claim as new and of my originality is—

The design for a bolt-operator and nail-set as herein shown and described.

In testimony whereof I have signed my name to this specification, in the presence of two subscribing witnesses, this 29th day of April, A. D. 1899.

CHARLES OAKS SEAVEY.

Witnesses:

ARTHUR W. CROSSLEY,
ANNIE J. DAILEY.
